UNITED STATES PATENT OFFICE.

GEORGE F. CONNER, OF PORT HURON, MICHIGAN.

ELEVATOR FOR GRAIN-SEPARATORS.

SPECIFICATION forming part of Letters Patent No. 722,945, dated March 17, 1903.

Application filed February 12, 1902. Serial No. 93,732. (No model.)

To all whom it may concern:

Be it known that I, GEORGE F. CONNER, a resident of the city of Port Huron, county of St. Clair, and State of Michigan, (whose post office address is care of Port Huron Engine & Thresher Works, Port Huron, Michigan,) have invented certain new and useful Improvements in Tailings-Elevators for Grain-Separators and Threshing-Machines, of which the following is a full, clear, and exact specification.

This invention relates to improvements in the elevators of grain-separators and threshing-machines which carry tailings from the screens back to the cylinders. If stones, loose bolts, nuts, and other hard foreign substances get into the sieves of a machine, they are picked up by this elevator and returned to the threshing-cylinder, thus passing again and again through the running parts to the great detriment of the latter.

This invention relates to means whereby these foreign substances are arrested during their passage through the elevator and deposited in a place from which they can be removed at will.

The invention consists in the matters hereinafter set forth, and more particularly pointed out in the appended claims.

In the drawings, Figure 1 represents a tailings-elevator of a separator embodying the features of my invention. Fig. 2 is an enlarged view, in longitudinal section, of the retaining-pocket.

Referring to the drawings, A represents the portion of the frame of a separator or harvesting-machine of the usual type contiguous to and supporting the lower sieves and carrier devices leading therefrom. A shaker is supported in the usual manner in the lower portion of this framework to receive the tailings from the sieves and convey them to the mechanism by which they are returned to the threshing-cylinder. The discharge end B of this shaker is adapted to discharge into the tailings-elevator.

An inclined tailings-elevator C is secured on the side of the main frame, so that its lower or receiving end catches the material discharged from the carrier B. Its upper discharge end is so disposed that the material raised by the elevator falls back into the ma-

chine in the usual manner. Said elevator comprises a closed chute c of suitable material and form, whose bottom plate c' for the 55 major portion of its length is traversed on its upper face by the blades, buckets, or other like devices of the conveyer-flight. As shown herein, the chute is rectangular in cross-section, thus being adapted for a chain and float 60 conveyer D. The latter comprises two or more parallel sprocket-chains d a short distance apart, running over sprocket-wheels d', journaled in either end of the chute. Said chains are connected at regular intervals with 65 floats or buckets d'', secured thereto in the usual manner and adapted to sweep the bottom of the trough and carry any material thereon upward to the top of the machine.

A pocket E is formed in the lower end of 70 the chute in its bottom wall just below the path of travel of the floats or buckets d''. Preferably and as herein shown this retaining-pocket is formed by deepening the chute for a portion of its length, commencing at its 75 lower end, so that its bottom plate e lies in a plane below the plane of the main bottom plate c' of the chute. The said bottom plate c' is connected at its end to the bottom plate e, its end c' being bent down to form a transverse partition or arresting-shoulder that prevents any upward progress of objects dropping into the pocket. Preferably the end wall of the chute, which is herein shown as curved to correspond to the sweep of the buckets 85 around the lower sprocket-wheel, is made to form an unbroken plane surface with this bottom plate. It is seen from this construction that the tailings which first fall from the mouth B of the shaker drop into the 90 pocket and there accumulate until a sufficient quantity has fallen there to form a bed over which the rest of the grain, &c., is swept. Any hard substances naturally gravitate to the bottom of the pocket, and as they are below the line of the buckets or floats they are 95 not disturbed. In case the accumulated tailings tend to crowd the foreign substances upward, through clogging between the bottom of the chute and the buckets, the transverse 100 partition arrests them.

It will be noted also that the retaining-pocket is in such a position that the tailings fall through the slackened chain as it passes

upward, and are thereby thoroughly agitated. This assists in allowing hard substances to fall below the line of the pockets or floats. While the retaining-pocket is thus directly beneath the discharge end of the shaker, it is so situated in regard to the lower sprocket-wheels that the tailings cannot retard the chain by becoming clogged between the latter and the sprocket. The weight of the chain is such as to cause it to reach its lowermost point when under motion just before the buckets sweep past the upper end of the pocket, and as a consequence the contents of the latter is kept thoroughly agitated. Thus the elevator-tailings do not become banked or jammed, but are continually passed upward, while the hard substances are retained. As a matter of convenience the lower plate of the pocket portion of the chute is removable secured in a suitable manner to the side walls to allow the pocket to be emptied as desired. As herein illustrated, this retaining-pocket is formed in a chute which is adapted for a chain conveyer. Obviously an endless screw or other like conveyer-flight might be used, in which case, of course, the bottom of the chute would be made to conform in transverse section to the path of travel of the conveyer-blades. The retaining-pocket, however, would be essentially the same and may obviously be applied to elevators other than those used on threshing-machines. Many different arrangements and details of construction may be used without departing from the spirit of the invention, and I do not limit

myself to any particular form of construction except as set forth in the appended claims.

I claim as my invention—

1. In a grain-separator, the combination of a tailings-elevator, a shaker discharging into said elevator at a point above its lower end, and a pocket in the elevator-chute below the path of motion of the conveyer-flight, and beneath the discharge end of the shaker and above the lower end of the chute. 40

2. In a grain-separator, the combination of a tailings-elevator, a shaker discharging into said elevator at a point above its lower end, and a pocket in the elevator-chute below the path of motion of the conveyer-flight, and beneath the discharge end of the shaker and above the lower end of the chute, said pocket being provided with a removable door on its lower side. 50

3. In a grain-separator, the combination of a tailings-elevator, sprocket-wheels at either end of said elevator, and a conveyer-flight comprising chain and floats operated by said sprocket-wheels, a shaker whose discharge end enters said elevator between said sprocket-wheels and a pocket in the elevator-chute beneath the discharge end of the shaker and above the lower end of the chute, said pocket being adapted to receive the slackened portion of the conveyer-chain as it leaves the 60 lower sprocket. 65
